UNITED STATES PATENT OFFICE.

MOSCOW E. BRIDGES, OF SHUBUTA, MISSISSIPPI.

LAMP BURNER AND CHIMNEY.

1,029,971.

Specification of Letters Patent. Patented June 18, 1912.

Application filed May 16, 1911. Serial No. 627,605.

To all whom it may concern:

Be it known that I, Moscow E. BRIDGES, citizen of the United States, residing at Shubuta, in the county of Clarke and State 5 of Mississippi, have invented certain new and useful Improvements in Lamp Burners and Chimneys, of which the following is a specification.

This invention relates to burners for oil 10 and similar lamps, and the primary aim of the invention is to provide novel means for so firmly holding the chimney of the lamp upon the burner as to positively prevent its falling from the burner.

15 The invention further aims to provide a novel form of chimney so constructed as to be firmly held by the holding devices of the burner in such manner as to prevent its being tipped over or pulled off of the burner 20 without disengaging the holding devices therefrom.

For a full understanding of the invention reference is to be had to the following description and accompanying drawings in 25 which:—

Figure 1 is a view partly in elevation and partly in section of the burner embodying the present invention. Fig. 2 is a bottom plan view thereof.

30 Corresponding and like parts are referred to in the following description and indicated in all the views of the accompanying drawings by the same reference characters.

In the drawings, the numeral 1 indicates 35 the threaded neck of the burner which neck threads into the usual opening in the top of the lamp font, and 2 the base of the burner, having a peripheral flange 3 which projects upwardly and outwardly and is cut away, 40 preferably at diametrically opposite points, as at 4. The chimney of the lamp is indicated by the numeral 5, and is provided, at its bottom, with a circumscribing flange 6 which fits within the flange 3 in the manner 45 illustrated in Fig. 1 of the drawings.

The devices provided for holding the chimney on the burner are constructed to engage with the flange 6 and hold the same firmly in place within the flange 3, and each 50 of these devices includes a strip 7 which is secured at its lower and inner end to the neck 1 of the burner and at its upper and outer end to the under side of the flange 3.

at the notch 4 therein. A pair of ears 8 is formed or provided upon each of the strips 55 7, and a chimney engaging finger 9 is also formed or provided with a pair of ears 10 through which and the ears 8 is passed a pin 11 serving to hinge the chimney engaging finger 9 upon the strip 7. A spring 12 is coiled about the pin 11 and at one end bears 60 against the strip 7 and at its other end against the finger 9, and serves to hold the upper end of the finger in engagement with the flange 6 of the chimney 5, the said upper 65 end of the finger projecting above the base 2 and being hooked, as at 13, to engage over the said flange 6. The engagement of the chimney engaging fingers with the flange of the chimney is such as to not only prevent the chimney being tipped over but also to prevent its being accidentally lifted from the burner. The portion of each chimney engaging finger projecting below the pin 11 70 serves as a finger piece and, the two fingers being oppositely located upon the burner, these finger pieces may be pressed toward each other by the thumb and finger of one hand while the chimney is removed by the other hand, such pressure exerted upon the 75 finger pieces serving to swing the upper ends of the fingers out of engagement with the flange of the chimney. 80

It will be observed from an inspection of Fig. 2 of the drawings that the strips 7 85 serve not only to support the chimney engaging fingers 9, but also serve as braces between the portions 1 and 2 of the burner and take the place of the ordinary braces which connect these parts. 90

Having thus described the invention, what is claimed as new is:—

1. In a lamp, a burner having a neck, a base located above the neck, strips connecting the neck and base and bracing the same 95 and supporting the base, spring-pressed chimney-engaging fingers mounted upon the said strips and having chimney engaging ends projecting above the said base, and a chimney having its lower end disposed upon the said base and provided with an outwardly projecting flange engaged by the said ends of the fingers. 100

2. In a lamp, a burner having a neck, a base located above the neck, strips connecting the neck and base and bracing the same 105

and supporting said base, the said base being formed with an upwardly and outwardly curved flange, a lamp chimney having its lower end disposed upon the said base and provided with an outwardly and upwardly curved flange fitting within the flange of the base of the burner, and spring-pressed chimney-engaging fingers mounted upon the said

strips and having hooked upper ends engaging over the flange of the chimney.

10

In testimony whereof, I affix my signature in presence of two witnesses.

MOSCOW E. BRIDGES. [L.S.]
